UNITED STATES PATENT OFFICE

CHARLES EDWIN RIFE, OF BALTIMORE, MARYLAND

PEA GRADER

Application filed August 4, 1927. Serial No. 210,619.

This invention relates to the grading of small articles such as peas and has for its principal object the provision of a machine for grading the peas or other articles in separate non-nested cylinders and aiding in the passage of the peas from one cylinder to another by a stream of water.

A further and important object of the present invention lies in the provision of a gear drive for each of the cylinders whereby the speed of any cylinder may be held at a very definite figure. A further object is the provision of a pea grading machine which requires no cleaning in the general sense of the word.

Up to the present time all pea graders have been driven indirectly, that is, the connection between the driving wheel and the grading cylinder has been such as to permit a slip between the two and this has been more or less essential in some of the machines and has been immaterial in others, particularly those having a plurality of concentric sieves. In the present device each and every one of the cylinders which are one less in number than the grades of peas, may be driven at the speed which has been found by practice to be correct for that cylinder.

Many workers in the art have taken pains to keep the water from the peas, holding that water will harm them but practical experience over quite a period of time has shown that this is not the case at all but that on the contrary the use of water to convey the peas from one grading cylinder to another is not only advantageous from the handling standpoint but actually is beneficial to the peas themselves and furthermore this water aids in the elimination of the daily cleaning of each cylinder, otherwise necessary and also eliminates any final washing of the peas since the grader itself performs this function.

In the present device the peas are fed into an elevated sieve A and are washed down a gentle incline to a lower sieve B and again to a still lower sieve C and are then elevated to a fourth sieve D at the same height as the entrance sieve A and from here are again washed down to a lower or fifth sieve E,

this last sieve passing the number 1 or smallest size peas and withholding for separate discharge the number 2 or second smallest size peas. Thruout the entire device the peas are always admitted to the feed end of the grader and each sieve discharges the grade retained by it to the opposite or discharge end of the machine making it very convenient to collect the graded peas.

In the drawings:

Figure 1 is a side elevation showing the feed end of the device.

Figure 2 is a side elevation on the opposite or discharge end.

Figure 3 is a side elevation.

Figure 4 is a feed end elevation of the B sieve.

Figure 5 is a discharge end elevation of the B sieve.

Figure 6 is a detail of the driving mechanism.

Figure 7 is a section thru a driving traveler.

Figure 8 is a detail showing the water discharge.

Figure 9 is a sectional detail thru an idler traveler.

The several cylinders are mounted upon a framework of any desired form, here shown as a plurality of upright rolled steel sections 80 to 10 to 15 connected by I-beams usually running from the top of one upright such as 15 to the next taller upright such as 14.

Power is received thru the pulley 30 and transmitted to the primary shaft 31 thru a clutch 32 having a handle 33 pivoted as at 35 to a bracket 36. On the primary shaft 31 are gears 38 and 40 driving respectively a beveled gear 41 on shaft 42 and a beveled gear 44 on shaft 45. Beveled gear 44 is in mesh with the gear 47 on the sloping shaft 48 which transmits power to longitudinal shaft 50 to which is secured the travelers 53 which drive both of the upper sieves A and D. A vertical shaft 55 at the elevator or feed end of the device transmits power to shaft 56 which drives sieve B which is at an intermediate height between the level of sieves A and D, and C and E.

Shaft 50 extends beyond the feed side and

power is transmitted from this shaft to the main elevator shaft 60 thru the sprocket chain 61 shown in the upper right hand corner of Figure 3. The details of this gearing and of the elevator itself conform to usual practice; the endless conveyer 64 with its buckets or flights 65 is shown in Figure 1 and the lower or idle shaft 67 of the elevator is also indicated in this figure.

10 The sieves A to E are substantially identical save that the perforated zinc cylinders have varying sized holes, those in A being $\frac{1}{2}$ of an inch in diameter and decreasing in size by one number (i. e., $\frac{1}{2}$ of an inch) down to the smallest or number 2 size which is $\frac{1}{2}$ ", therefore retaining the Number 2 peas while permitting $\frac{1}{4}$ inch diameter peas, Number 1 size, to pass. The sieve B which is at an intermediate height is shown in larger scale in 15 Figures 4 and 5, similar to the views of the same element in Figures 1 and 2, respectively. The characters denoting the similar elements of the other sieves follow the numbering of 20 parts of B differing only in the initial capital letter.

25 Sieve B consists of two identical cylinders B1 of sheet metal preferably zinc perforated to withhold the larger size of pea admitted to the sieve and to pass peas of smaller sizes. 30 Each sheet is permanently secured to a circular angle member B2 and these two angle members are secured together with their transverse flanges back to back so that the two zinc cylinders form to all intents and purposes a single piece. At the discharge end of the zinc cylinder is secured a ring B3 having a central, radial, integral, cut gear B4. A similar ring is at the feed end as the two ends of each sieve are positively driven. At 35 the center, each sieve is supported by an idling traveler B5 in a bearing B6 and at each end each sieve is supported by two quite similar but geared travelers, one a driver and the other an idler, these being on the drive shaft 56 and idle shaft B7 respectively, the driving traveler being numbered B8 while the idling traveler is denoted B9. It will be noted however, that both B8 and B9 are geared while B5 is not geared since it engages the 40 flanges B2. The sieve B is therefore supported entirely by the six travelers and these in turn are supported by the longitudinally extending I-beams 20 and 21, the bearings in each case being given the numeral 6.

45 At the feed end of the sieve B and within the circular stiffening angle member B10 is a plate B11 supported from the framework by anchor pieces B12. The plate B11 communicates with a curved pipe A14 leading from the near or bottom end of the trough of the sieve with the next larger openings, i. e., the one that withholds the next larger size peas, in this case, sieve A. The peas which 50 pass thru the sieve—in the case of sieve B this will be sizes 1, 2, 3 and 4—drop down-

wardly from the sieve cylinder B1 to a trough B15 which has a flat feed end plate at the very bottom of which is a circular orifice B16 delivering the peas to the curved pipe B14 exactly like the semi-torus pipe A14 at the discharge end. There is a plate B20 supported from the transverse angle piece B21 by means of brackets B22. This discharge end plate B20 leads vertically downward to a discharge pipe B23 which curves outwardly and away from the machine as best seen in Figure 3 and delivers the single grade of peas to a container or bin, not shown.

55 The water which performs an important feature in the present invention is delivered thru a riser B25 receiving water from the horizontal main water pipe 75. At the top of this riser pipe B25 is an L B26 leading to the horizontal spray pipe B27, there being a valve B28 to control or shut off the water from the spray pipe which runs the entire length of the sieve and is capped at its far or feed end as at B29. The operation of the spray pipe is best shown in Figure 8, the stream of water being denoted by the letter w. It will be noted that the plane of the streams of water discharged from the orifices in the spray pipe B27 is substantially tangent to the perforated zinc plate B1 but that by gravity the streams swerve and strike the bottom wall of the trough B15 not far from the pipe B27. The holes in the spray pipe are not of the same size but increase in size from the valve end to the cap end altho this is not at all essential even tho the entire length of the sieve is used for grading. Purely for economy the vertical water pipe for sieve A corresponding to B25 is omitted and the longitudinal spray pipe A27 receives its water supply thru a transverse water pipe 82.

60 Referring now more particularly to Figure 1, the mass of ungraded peas is delivered to a hopper 76 in plate A11, this hopper taking the place of the entrance opening B13 in the next lower grader. The largest peas are withheld by this sieve A which revolves in the same direction as the sieve D since it is preferred in at least some types to drive both of these upper sieves from the same driving traveler 53, the travelers A9 and D9 being idlers as in the other sieves. In those cases where it is desired to drive the sieve D at a different speed, the sieves A and D are shifted longitudinally just a bit so that the gear D4 will not mesh with driving traveler 53, and to connect the drive shaft 50 with the shaft 78, so that the latter becomes a drive shaft, and providing idlers loose on shaft 50.

65 The peas passing from A are delivered thru A14 to B which retains and discharges the Number 5 peas, the other grades passing thru the zinc sieve plates B1 to the trough B15 and thence to C which retains and discharges the Number 4 size. The trough C15 instead of discharging to a pipe such as B14

discharges to the endless belt conveyer or elevator 64 housed in casing H, the buckets discharging at the upper portion of the elevator to a chute 80 which delivers the last three grades of peas to a hopper 81 practically identical with hopper 76 of sieve A.

Grades 1 and 2 pass from the trough D15 to somewhat elongated pipe D14 discharging to the final sieve E, the trough E15 of which differs from all other troughs in that it slopes downwardly toward the discharge end instead of discharging downwardly to the feed end as is the case with the other troughs. The trough of E has a discharge pipe E30 while the discharge hopper E31 delivers the smallest or Number 1 peas which have passed thru the holes of the sieve plates 31.

Due to the constant play of water on each of the sieves the peas are kept in much better condition than if handled entirely mechanically and at the same time the great advantage is had that the peas are washed as they are graded. Each of the sieves are rendered self-cleaning by means of wooden rollers B32 (see Figure 5) covered on the outside with crepe rubber indicated as at B33 and fitting quite loosely on a bar B35 held by links B36 pivoted in brackets B37 secured to the longitudinal upper I-beams such as 22. The great play, clearly shown in Figure 5, permits each section of the roller to ride over an obstruction but to press lightly at all times against the zinc cylinders and to push back thru the holes or perforations any peas that may be wedged therein. The roller rods B36 may be spring-pressed but generally gravity is ample to afford the desired light pressure. While I prefer to drive the several sieves at the speed best suited to the particular grade, all the sieves may readily be driven at uniform speed by having the beveled gears of the same size, and the device is sometimes made in this manner in actual practice.

45 What I claim is—

1. The art of grading peas which consists in passing the entire mass of peas to a sieve to retain the largest size peas, forcing water into said sieve to thereby cushion the peas in the sieve, catching the ungraded peas passing thru the first sieve on a cushion of water, washing said peas down to a second sieve which retains the next larger size, and in cushioning and washing the peas downward from the second sieve to the third sieve.

2. In a pea grader, a plurality of cylindrical sieves arranged parallel to each other between two parallel end frames and at a plurality of elevations, positive gearing for simultaneously driving all of said sieves, conveying means connecting successive sieves, and means for discharging water thru said means to cushion and aid in the conveying of the peas from one sieve to the next lower sieve.

3. A cylindrical sieve, means for driving said sieve, a plurality of rollers each covered with crepe rubber resting lightly on the periphery of the sieve, and means for discharging a plurality of streams of water against the periphery of the sieve approximately diametrically opposite to the line of said rollers.

4. A pea grading sieve consisting of a cylinder of perforated metal, a ring at each end of said cylinder, a gear in each ring, a plurality of geared travelers meshing with the ring gears and supporting the sieve, one of said travelers being positively driven, a V-shaped sloping trough having a rounded bottom beneath said sieve, and means for discharging water against the periphery of the sieve to drain into the sieve and convey the peas falling thru the sieve down said trough.

5. A pea grader comprising, in combination, a plurality of cylindrical sieves of different mesh having substantially parallel axes located between two frames and at different elevations, the feed ends of said sieves being all located at one side of the grader, chutes at the discharge ends of said sieves adapted to receive and convey the peas retained by the sieves, means for introducing into the feed end of the uppermost sieve a mass of ungraded peas, a trough beneath each sieve sloping downwardly towards the feed end thereof, a chute communicating with the lower end of each trough except the lowermost trough adapted to discharge into the feed end of the next lower sieve, and means for conveying the peas from the lowermost trough to an upper sieve, and a lower sieve into which the peas passing thru the last mentioned sieve are discharged.

6. The art of grading peas which consists in feeding the peas to a separator which separates a single grade of peas, forcing water into the sieve to thereby wash and cushion the peas, washing the ungraded peas from such separator on a cushion of water and washing them downwardly to a separator at a lower level, washing the ungraded peas from said second separator on a second cushion of water and washing them downwardly to an elevator, discharging to a third separator at a high level and washing the ungraded peas from said third separator onto a cushion of water and washing them downwardly by gravity to a fourth separator at a level below that of the third separator.

7. The device of claim 4 including water conveying means for conveying the ungraded peas passing thru one sieve by gravity, and elevator means for conveying the washed peas upwardly to the second sieve.

8. A nest of pea graders consisting of a series of sieves at different levels, and a further grader beneath said series of graders, a frame for supporting said nest, and means

for conveying peas thru the series of graders and finally to the other grader.

5 9. A nest of graders consisting of a series of graders arranged at successively lower elevations, a second series of graders also arranged at successively lower elevations, one of the graders of the second series being beneath the graders of the first series, and means for conveying peas thru one series of graders and then thru the other series.

10 10. A nest of pea graders consisting of three graders arranged side by side and at successively lower elevations, and a fourth grader directly beneath the highest grader at the same elevation as the third grader, and means for conveying peas from the highest grader to the grader directly beneath via the other two graders.

15 11. In a pea grader, a plurality of laterally arranged substantially parallel cylindrical sieves of different size mesh, a gear secured to the periphery of each sieve, a plurality of idle travelers, a single geared traveler in mesh with the peripheral gears of two sieves, water conveying means for conveying the ungraded peas passing thru one sieve by gravity, and elevator means for conveying the washed peas upwardly to one of said two sieves.

20 30 In testimony whereof I affix my signature.
C. EDWIN RIFE.
